CARBON DIOXIDE DISCHARGE SYSTEM

Filed July 16, 1942

UNITED STATES PATENT OFFICE

2,373,037

CARBON DIOXIDE DISCHARGE SYSTEM

Charles H. Lindsay, Elmira, N. Y., assignor to
American-La France-Foamite Corporation, Elmira, N. Y., a corporation of New York

Application July 16, 1942, Serial No. 451,129

8 Claims. (Cl. 62—1)

The invention relates to aircraft fuel systems and more particularly to systems for delivering carbon dioxide gas into aircraft fuel tanks for the purpose of avoiding development of ignitable vapors in the space above the liquid fuel therein. Ordinary carbon dioxide discharging systems applied to this purpose have the objection that they do not function reliably because they store the dioxide in the highly compressed liquid form, and, when discharging through the fine orifice necessary to give the required slow rate are subject to stoppage from the freezing of any water with which the dioxide may be contaminated or which may find its way into the system. It is difficult to obtain carbon dioxide entirely free from moisture, also to keep moisture from condensing within the tubing of the system, and even less than 1% can defeat a proper discharge for the purpose indicated, by clogging the fine nozzle orifice with water ice. This may occur either from ice as fine particles frozen while suspended in the flowing dioxide, or as vapor, or as an ice film freezing on the inside of, and thereby closing the nozzle tip. The freezing temperature occurs from the rapid expansion of the dioxide as its pressure is relieved and as it changes from liquid to vapor form. The temperature drop is most pronounced at the nozzle tip, but water-freezing temperature can arise at any point along the line from the tip back to the storage flask during the discharge. It is of great importance that the discharge when started shall be complete and uninterrupted throughout the required period. These systems are put in use just before engaging in combat and their failure might mean disaster.

This invention is a liquid dioxide discharge system rendered free of all danger of ice-clogging, by virtue of a special construction and organization of the discharge passage which forestalls the movement of water, whether in vapor, liquid, or solid form, so far through the discharge line as to reach the cold nozzle tip. As above indicated, the water may be present in liquid or vapor form, and it may also be in solution in the liquid dioxide. This latter fact, as well as the fact that the specific gravities of water and liquid dioxide are normally not very different, may account for the failure of the ordinary precautions, such as short dip-tubes, to prevent discharge of the water, in addition to which note must be taken of the ebullient condition of the liquid dioxide which begins on the instant of any release of pressure, as on discharge, so that if the water could be assumed to have collected as a pool in the bottom of the flask the internal ebullient commo-

tion would of course tend to scatter it throughout the mass of the dioxide, thus encouraging its entry into the discharge line. Proceeding on the theory that the water and liquid dioxide are not susceptible of sharp separation for the reason mentioned, the discharge passage of this invention includes the combination of two different types of water-restraining agencies, one involving a labyrinthic entrance to the discharge line and the other a refrigerated eliminator at the other end, so that moisture in any of its forms is precluded from reaching the tip. This combination has been found consistently safe in operation and has been accepted as such, giving reliable discharges even in cases where water has been purposely added to the dioxide for test purposes in amounts as high as 1.5% by weight and which of course is far greater than would be experienced in practice.

20 The accompanying drawing shows the preferred form of the new discharge passage, Fig. 1 being a diagrammatic section of the system, Fig. 2 an enlarged section of the labyrinthic receiving end of the passage, Fig. 3 an axial section of the nozzle and Fig. 4 a modified form of the water-drainage provision.

25 The liquid dioxide container or flask and its operating head 1 will be recognized as conventional and will be understood to confine the liquid under a pressure in the neighborhood of 850 lbs. at normal temperatures. An example of such operating heads will be found in Patent No. 1,921,411, which is well known to those skilled in this art. On opening the operating head, as by 30 perforating the sealing disc therein as customary, liquid dioxide flows upwardly through the dip tube structure 2 and thence through the piping 3 to the nozzle 4 in the fuel tank 5 to be protected. It will be understood that the discharge 35 passage starts at the foot or entrance to the dip tube structure and ends at the nozzle orifice, which is of smaller size than customary in dioxide systems, being in the order of from .025 inch to .040 inch diameter. Such fine holes are 40 required in order to prolong the discharge period and also to avoid excessive pressure within the fuel tank. Because of their small size they are 45 peculiarly susceptible to stoppage.

50 The dip tube structure is screwed to the flask head 1 or otherwise supported in the flask opening and is preferably formed of telescopic sections, marked 2 and 6, urged apart by an intervening coil spring 7. This presses the lower section 6 downwardly thereby maintaining the foot 55 of the tube in contact with the flask bottom, re-

gardless of variation in the lengths of different flasks with which it may be used, thereby insuring a maximum liquid evacuation of the flask when discharged, and at the same time steadyng the structure against vibration.

The lower telescopic section 6 contains or constitutes the labyrinthic receiving entrance above referred to. It comprises an inner inserted cylindrical member or tube 8 appropriately mounted therein to form therewith an annular chamber or passage 9, which is shallow in proportion to its circumference and width. The entrance thereto is at its lowest point, provided by a ring of radial holes 10 and the exit therefrom is by radial outlet holes 11 at its top leading into the interior of the inserted member 8. Liquid dioxide enters the lower holes by horizontal flow in the flask proper and then flows first upwardly through this shallow passage, thence inwardly through the radial holes 11 and thence upwardly again into the upper section 2 and onwardly through the piping 3 toward the nozzle. The cross sections of the annular chamber 9 and of its entrance and exit holes are substantially equal to the cross section of the tube 2, or at any rate equal to that of the perforation made in the sealing disc so that the flow occurs without any particular restriction or choking effect at this point. The construction constitutes a water-restraining means, functioning apparently by the impingement of the liquid on the surfaces of the shallow passage, which holds the water or some of it back, by causing it to adhere to such surfaces. After the discharge is over the water so retained can be found, usually then frozen, in the labyrinthic passage.

From this water-restraining means the dioxide passes on through the piping to the nozzle 4, where the flow is intercepted by a pervious partition of extended area and which may be nothing more than a fine-textured, woven-wire screen 12, of proper size and made of metal or other good conductor of heat and preferably in tubular form. One end of this screen is attached (at 13) around the interior neck of the nozzle tip 14 and preferably by soldering it thereto so as to establish a good thermal connection therewith. The tubular screen is of extended length, many times its own diameter, and being closed at its free end all of the dioxide must pass through it in order to reach the nozzle.

At the time of discharge the nozzle tip instantly acquires a sub-zero temperature as the effect of the abrupt expansion through its orifice, and the soldered connection transmits this low temperature to the screen so that water, even in so fine a state as to be regarded as dissolved in the dioxide, encountering this cold metal mesh is promptly frozen thereon and therefore does not reach the tip. At the same time such particles of water or water vapor as may have become frozen in the piping before reaching the screen are also caught by it and thereby kept from plugging the tip. The screen thus serves as a moisture eliminator both by its refrigerating action on dissolved or liquid water and by its mechanical screening action. In the latter respect its action is no different from screens which have heretofore been interposed in the flow of gas discharge, except that its area is many times that which would be required if only scale and dirt were to be excluded and hence it is free from danger of itself becoming a stoppage to the flow. Together with the labyrinthic entrance the total effect is, as already stated, to provide assurance

of continuous discharge during the effective discharge period and notwithstanding the fine size of the discharge outlet with which these systems must be provided.

5 I have found that the refrigerated screen tends to collect less frost when the dioxide entrance into the dip tube or into a shallow chamber therein, such as the chamber 9, is by horizontal flow as through the radial holes 10, rather than by way 10 of a dip tube that is open-ended at its foot, indicating that such direction of entering is a factor in the result, and also that it is still further reduced by locating a flange 15 immediately below such radial holes, and I accordingly prefer this 15 construction of the receiving entrance.

Since it is obviously desirable that no water should remain over in the flask when recharged with dioxide, provision for the removal of any such water is provided by forming the inner or impingement member 8 of the dip tube with a tubular extension 16 closed at its end and constituting the very foot of the dip tube, pressed against the flask bottom by the telescope spring as above pointed out. This extension is in line 20 with the axis of the dip-tube and provided with a lateral port normally closed by a ball valve 17 and spring 18. By inserting a proper suction tube through the flask head and pushing it into this extension, the ball 17 can be unseated, letting any water in the flask bottom flow into the extension, so that it can be sucked up by the tube, thus removing any residuum of water in the flask before recharging it with dioxide. This 25 is much easier than unscrewing the discharge head to drain out water.

An alternate method of water-drainage, as indicated by Fig. 4, may in some cases represent the preferred form, as for instance where the dip-tube is curved or otherwise obstructed against the use of a suction tube. In such cases this 30 same water drainage valve can be located at or in the head itself, as indicated at 19 in this figure. When such valve is pressed open by a suitable tool introduced through the opened head, the 35 flask being inverted, any water can be drained out.

I claim:

1. A carbon dioxide system comprising a flask 40 of liquid dioxide having a discharge passage terminating in a discharge nozzle at which the liquid expands to vapor phase and including a tubular conduit within the flask, an interior member co-acting with said conduit to form a shallow annular chamber therewith; said chamber being 45 closed at both its ends and provided with lateral holes near its lower end to receive dioxide and lateral holes near its upper end through which dioxide passes in its course toward said nozzle, the cross area of said shallow chamber and the 50 aggregate areas of said holes being not substantially less than that of the discharge passage elsewhere.

2. A carbon dioxide discharge system comprising a flask of liquid dioxide having a discharge 55 passage comprising a dip-tube within the flask connected to a discharge nozzle through which such liquid expands to vapor phase and means for retarding the passage of water in the dioxide to said nozzle comprising said dip-tube closed at its lower end, a radially projecting flange on said closed end and lateral dioxide entrance holes leading into such tube just above said flange.

3. A carbon dioxide system comprising a flask 60 of liquid dioxide having a discharge passage including an interior tubular conduit and means for

removing any water retained in the flask comprising a valve port in said conduit, a valve normally closing such port, said valve being operable by an instrument inserted into said conduit for the removal of water through the port.

4. A carbon dioxide system comprising a flask of liquid dioxide having a discharge passage including a dip-tube having a closed foot with dioxide entrance holes above said foot, a valve port in said tube adjacent the foot and a valve for said port arranged to be opened by an instrument introduced through said dip-tube and adapted to allow water in the flask to enter said dip-tube below the holes therein.

5. A carbon dioxide system comprising a flask of liquid dioxide having a discharge head formed with a tubular part projecting into the flask, a port in such part and a valve for said port located to be openable by an instrument inserted through the discharge head, whereby water collecting in said flask can be drained out through said head.

6. A carbon dioxide system for slow discharge into a fuel tank comprising a flask of liquefied carbon dioxide having a discharge passage comprising a tube within the flask and piping connecting such tube to a nozzle within said tank, said tube having its only entrance organized in the form of labyrinthically related holes and located in the lower part of the flask to cause said passage to conduct only liquid dioxide during the effective part of the discharge period, such entrance holes being of such area as to offer no greater resistance to flow than any other part of such discharge passage and said nozzle having a fine orifice suited for discharging into a fuel tank.

7. A carbon dioxide discharge system for slow discharge into a fuel tank comprising a nozzle in said tank, a flask of liquid dioxide having a dis-

charge passage including a tube within the flask organized to receive only liquid therefrom during the effective part of the discharge period and piping connecting such tube to the nozzle in the

5 tank having a restricted orifice through which the liquid dioxide expands to vapor phase, said orifice constituting the point of maximum restriction to the outflow of the liquid dioxide and said passage including a water-restraining means 10 associated with the foot of said interior tube in the flask and a second water-restraining means constituting part of said nozzle capable of retaining water vapor closely associated with said orifice in the nozzle, and means at the head of 15 the flask normally confining the liquid dioxide therein adapted to be opened to permit immediate unrestricted flow through said discharge passage.

8. A carbon dioxide system for slow discharge into a fuel tank comprising a nozzle in said tank, 20 a flask of liquefied carbon dioxide having a discharge passage comprising a tube within the flask and piping connecting such tube to a nozzle within said tank, said tube being closed-ended and having its only entrance organized in the form of 25 holes in the side wall of said tube located in the lower part of the flask to cause said passage to receive only liquid from the flask during the effective part of the discharge period, such entrance holes being of such area as to offer no 30 greater resistance to flow than any other part of such discharge passage and said nozzle having a fine orifice suited for slowly discharging into a fuel tank and containing a fine screen partaking of the subzero temperature at said orifice and intercepting the flow thereto, said screen 35 having sufficient area to freeze and retain thereon any water encountering it without itself becoming a stoppage to flow.
